UNITED STATES PATENT OFFICE.

JOHN C. CALDWELL, OF MIAMI, FLORIDA.

POWER-GENERATING MECHANISM.

Application filed November 2, 1921. Serial No. 512,370.

To all whom it may concern:

Be it known that I, JOHN C. CALDWELL, a citizen of the United States, residing at Miami, in the county of Dade and State of Florida, have invented certain new and useful Improvements in Power-Generating Mechanism, of which the following is a specification.

This invention relates to water motors and 10 more particularly to an improved device whereby electrical or mechanical energy may be derived from a current of running water in a stream and converted to different uses.

The primary object of the invention is 15 the construction of a floating barge wherein a plurality of parallel rows of propellers are mounted for rotation by the current of a stream of running water in such manner that the power derived may be communicated 20 to a single or a plurality of rotating shafts and produce electrical or mechanical energy on the barge proper, permitting said energy to be communicated to some distant point as the case may be.

25 A still further and very important object of the invention is the construction of a water motor of the class above set forth, wherein the barge is provided with a plurality of parallel tunnels having propellers 30 mounted therein to be driven by the current from a running stream for instance, including a heating arrangement disposed between the parallel rows of tunnels, whereby the ice accumulation may be avoided when the 35 motor is used in cold weather.

Another and very important object of the invention is the construction and arrangement 40 of a barge having a power generating mechanism so that the mechanical or electrical power derived from a running stream of water may be communicated to some distant point or the barge itself converted into a work shop, whereby continuous power may be had at all times and at the lowest 45 possible cost.

A continued object of the invention is the construction of a power generating barge capable of use wherever power may be derived from a running stream of water and 50 one in which the parts are extremely simple in construction, easily assembled, rigid and durable, highly efficient in operation, practical and capable of being manufactured at a very low cost, whereby its commercial 55 possibilities are greatly enhanced.

The invention will be best understood

from a consideration of the following detailed description taken in connection with the accompanying drawing forming a part of this specification, with the understanding, 60 however, that the invention is not confined to any strict conformity with the showing in the drawing, but may be changed and modified so long as such changes and modifications mark no material departure from 65 the salient features of the invention as expressed in the subject matter being claimed.

I attain the above objects and others by the accompanying drawings, wherein:

Figure 1 is a longitudinal view through 70 the barge showing the brake mechanism and drive wheels for the propellers.

Figure 2 is a similar longitudinal view showing the arrangement of the propeller wheels.

Figure 3 is an enlarged transverse, sectional view showing the power operating mechanism in its relation with the propeller shaft and wheel.

Figure 4 is a sectional view taken on the 80 line 4-4 of Figure 3.

Figure 5 is a further section taken on the line 5-5 of Figure 3.

Figure 6 is a sectional view taken on the line 6-6 of Figure 3.

Figure 7 is a view taken on the line 7-7 85 of Figure 3.

Figure 8 is a detail view, partly in section of the compressed air system for operating the brake mechanism; and

Figure 9 is a perspective of a key.

Referring now to the drawing, wherein like reference characters designate corresponding parts throughout the several views, I have shown my invention wherein 95 the power operating mechanism is preferably installed on a suitable floating barge having a top 5, front and rear ends 6, 7, and a central flooring 8, dividing the barge into an upper story 9 and a lower story or compartment 10. The lower story, above referred to, as well as the upper story, is provided with inner walls 11, 12, extending longitudinally of the body of the barge and in the lower section thereof I have provided a 100 plurality of tunnels designated at 13, 14, in which the propellers and propeller shaft operate, whereby power may be communicated and generated from the current of a running stream. The bottom flooring 15 is connected with the side walls 16, and that portion of the flooring between the parallel tun- 105 110

nels is provided with inclined beams throughout the entire length of the barge shown at 17, 18, so that the current of the stream will be directed to the respective tunnels and consequently rotate the propellers on the operating mechanism, now to be described in detail.

Within each tunnel above referred to, I have provided a plurality of propellers and 10 propeller shafts 20, 21, journaled between the inner walls 11, 12, and inner-partitions or walls 22, said propellers being of substantial width but permitting sufficient clearance between the walls of the tunnels for their 15 proper operation, yet permitting the passage of refuse and other matter beneath the barge which might accumulate therein. I have preferably provided each propeller shaft with ten blades, so that at least 3 of 20 the same will be at all times immersed in the stream but normally the water line W will be at a point just below the propeller shaft as suggested by Figure 5 of the drawing.

The central air passages 22^a between each 25 of the adjacent tunnels are provided with heaters 23 with upwardly extending, radiating pipes 24 leading into the respective tunnels so that in cold weather the propellers or blades may receive sufficient heat so as to 30 prevent the accumulation of ice thereon and consequently avoid the clogging of the tunnels with ice due to the spray of the stream, which might otherwise prevent the operation 35 of the propeller blades.

Each propeller shaft 21 is provided with 40 a drive wheel 25 which communicates power to a line shaft 26 journaled in bearings in the sides of the barge through a pulley and belt arrangement 28, 29. The line shaft 45 also carries a rotatable pulley 30 and belt 31, whereby the dynamo 32 positioned at one side and preferably in a compartment 33, adjacent the side wall of the barge is operated, so that the electrical energy may 50 be generated and conducted to some distant point through suitable wiring, not shown. It will thus be seen from this construction that I have provided a simple and highly efficient operating mechanism, whereby the 55 current from a stream may generate electrical power so that the same may be conducted and utilized wherever desired at any distant point or to a mill or factory adjacent the stream and thus dispense with the necessity of erecting a dam or other highly expensive power operating machinery of a permanent character.

In addition to generating electrical power, the apparatus also contemplates the generation 60 of mechanical power through aligned pulleys 35, 36, on the line shaft 26 and a second line shaft 37, disposed in the upper story of the barge, the respective pulleys being driven by a belt 38, as clearly shown in 65 Figure 3 of the drawings. An electrical

motor 38' and the usual variable speed pulleys and belt arrangement 39, 40 are operably connected with the shaft 37 through the clutch and clutch lever 41, 42, whereby any suitable type of tool may be driven and 70 for this reason mounts for tools designated by 43 are secured on the flooring of the upper story, thus permitting the barge to be converted into a machine shop or plant, whereby continuous rotary power may be 75 utilized to operate the machinery.

Referring now in particular to Figure 4 of the drawing, it will be observed that each drive wheel 25 is provided with a crank arm 44, connected to a crank shaft 45, one 80 end of said crank shaft being connected by an actuating member 46, pivotally connected as at 47 to a slide rod 48, operable in a suitable guide 49 positioned adjacent a compressed air cylinder 50. The hooked end 85 51 of the slide rod (see Fig. 8) is adapted for engagement with a spring latch 52, normally held by the spring 53 in engagement with the said slide rod 48.

This latch is carried by the cross head 90 which is connected to the piston rod 54, whereby the piston rod 54 may operate and force the air through the proper valves 55, 56 to be utilized in operating the brake mechanism, subsequently to be referred to. 95 A longitudinally extending brake rod 57 has connected thereto the brake members 58, pivoted as shown at 59 so that when the brake rod 57 is actuated the said brake members will engage the brake drums 60 100 on the shaft 21 and consequently limit the rotation thereof. Referring in particular to Figure 8, it will be observed that one end of the brake rod 57 operates in a cylinder 62, so that when the valve 63 is raised 105 from its seat the compressed air will act on the piston head of the brake rod 57 and force the same rearwardly, consequently moving the braking members 58, above referred to. To release the braking mechanism the valve 63 is moved into its seat and the pet cock 65 is opened, an exhaust port 66 being provided for the obvious purpose. When the tank 50 has been properly charged with the compressed air and it is 110 desired to disconnect the piston 54, the key 67 is inserted and bearing against the end of the latch member 52 against the resistance of the spring will raise the hooked end of the said latch and disengage the 115 same from the sliding member 48, so that the same may operate without moving the said piston rod 54. In this manner it will 120 be readily seen that the operation of the drive wheels 25 afford means for maintaining a compressed air storage tank continually charged and permit of the utilization of the compressed air for operating different kinds of machinery, wherever so desired.

125

130

In the accompanying drawings, I have illustrated my invention embodied in one form by way of example, and which in practice has been found to be highly satisfactory in obtaining the desired results. It will be obvious however, that other embodiments may be adapted, and that various changes in the details of construction may be resorted to by those skilled in the art without departing from the spirit and scope of the invention. It is furthermore understood that the invention is not necessarily limited or restricted to the precise elements shown except in so far as such limitations are specified in the subject matter being claimed.

Having thus described and illustrated my invention, what I claim as new and desire to secure by Letters Patent is:

20. 1. A power generating mechanism in combination with a barge having a plurality of tunnels in the bottom thereof, the tunnels having their lower ends open to permit the free flow of water therethrough, horizontal propeller shafts and propellers mounted thereon, operable in the tunnels by a current of water, means for heating said tunnels, drive wheels on each end of the propeller shafts, common line shafts and a pulley and belt mechanism for driving said line shafts from the drive wheels, a second line shaft driven by each of the first mentioned line shafts, means for producing compressed air by the rotation of the propeller shafts and means for releasing said compressed air to vary the speed of rotation of the respective line shafts.
25. 2. In a means for generating power from flowing streams, a single barge having a plurality of parallel longitudinally extending spaced channels formed therein having their lower ends open for permitting the free flow of water therethrough, closed passageways arranged between the channels, a plurality of transversely aligned water wheels mounted in said channels, means for connecting the transversely aligned water wheels together, means for operating a plurality of independent line shafts from the means for connecting the transversely aligned water wheels together, means operatively connecting the water wheels disposed in longitudinal alignment together, means for operating a compressed air motor from the longitudinally aligned water wheels, heaters disposed in said closed passageways between the channels, and oppositely extending heat conveying pipes connected with the heater and arranged to communicate with said channels.
30. In testimony whereof I affix my signature in presence of two witnesses.

JOHN C. CALDWELL.
